UNITED STATES PATENT OFFICE.

FRANK McCARROLL, OF DALLAS, TEXAS.

AEROPLANE.

1,152,743.

Specification of Letters Patent.

Patented Sept. 7, 1915.

Application filed November 8, 1911. Serial No. 658,328.

To all whom it may concern:

Be it known that I, FRANK McCARROLL, citizen of the United States, residing at Dallas, in the county of Dallas and State of Texas, have invented certain new and useful 5 Improvements in Aeroplanes, of which the following is a specification.

This invention relates to new and useful improvements in aeroplanes.

10 The object of the invention is to provide a plane or wing for an aeroplane comprising a relatively fixed section and forward and rearward adjustable sections hinged to the forward and rearward lateral edges of 15 the fixed section. The particular object of such an arrangement is to vary the curvature of the plane from front to rear and by this means the plane may be so adjusted as to reduce the "head resistance" to a 20 minimum.

Another object is to provide suitable 25 means for manipulating the adjustable sections whereby the movable sections of a plane may be simultaneously swung upward or downward; or by which the adjustable sections of a pair of planes may be swung in opposed relation to retain the lateral equilibrium of an aeroplane.

It is obvious that the running gear of an 30 aeroplane offers more or less resistance to the forward movement of the same and this is termed "head resistance."

One of the objects of this invention is to swing the running gear up into the frame 35 of the aeroplane whereby it will offer less resistance to the forward movement of the aeroplane than where said running gear hangs pendant from the frame.

A still further object of the invention is 40 to provide a machine that will be strong, durable and efficient and comparatively simple to construct, also one in which the several parts will not be likely to get out of working order.

45 With the above and other objects in view the invention has relation to certain novel features of construction and operation, an example of which is described in the following specification and illustrated in the accompanying drawings, wherein:

Figure 1 is a plan view of the forward portion of an aeroplane equipped with this invention, Fig. 2 is a side elevation of the same aeroplane, Fig. 3 is a transverse vertical sectional view on the line $s-s$ of Fig. 2, Fig. 4 is a transverse sectional view of one

of the planes, Fig. 5 is an enlarged detail transverse section through one of the planes, Fig. 6 is a detail of the adjusting means for the planes, Fig. 7 is an elevation of the 60 parts illustrated in Fig. 6, but shown at right angles thereto, and Fig. 8 is a horizontal cross sectional view on the line $x-x$ of Fig. 6.

In the drawings the numeral 1 designates 65 the frame of a monoplane and it will be noted by observing Fig. 3 that this frame is triangular in cross section. It has been customary to make these frames rectangular in cross section and it is believed the 70 shape of frame herein shown will offer less resistance to the forward movement of the machine than those now commonly in use. At the rear of the frame a suitable rudder 2 and rear planes 3 are provided. A skid 75 4 depends from the rear end of the frame for supporting the same when on the ground. At the forward end of the frame a suitable propeller 5 is mounted and connected to an engine 6 also carried in the 80 forward portion of the frame.

At each side of the frame near the forward end wings 7 are secured and extend laterally on each side of said frame in the usual manner. As the construction of one 85 wing is substantially the same as the other a description of one will suffice for both.

The wing comprises a forward section 8, an intermediate section 9 and a rear section 10. The sections are formed of transverse upper 90 and lower ribs 11 and 12 respectively which are secured to longitudinal I-beams 14 interposed between the upper and lower ribs. On these ribs fabric 15 is fastened so that

the sections will have upper and under surfaces. The said sections are constructed 95 separately but so shaped that when assembled a complete and properly curved plane will be produced. The intermediate section 9 is fixed to the frame 1 and is suitably supported against movement. The other sections are hinged to the fixed section and are adjustable.

The hinged joint between the sections may be made in any approved manner and in Fig. 5 I have shown flanged 100 hinged members 16 connected together and secured to the adjacent I-beams of the sections. For covering the joints between the sections flaps 17 are provided and directed rearward so as to cover the spaces at the 105 joints and lie in close contact with the fabric coverings when the machine is in operation.

2

A tubular rock shaft 18 extends longitudinally through the section 9 and is supported in bearings 19 secured to the inner sides of the ribs 11 and 12 between the 5 same. On this shaft cross arms 20 are centrally secured so as to project on each side of said shaft. The free ends of the arms terminate in close proximity to the ribs and are provided with suitable means for fastening 10 the inner ends of flexible connections 21 and 22 respectively thereto. The connections 21 extend forward through the I-beam and are fastened to the rear I-beam of the section 8; while the connections 22 are 15 crossed and pass through the I-beam and fastened to the forward I-beam of the section 10.

By the above arrangement the sections 8 and 10 are held in position and when the 20 rock shaft is swung it is obvious that said sections 8 and 10 will be moved in unison either up or down. It is to be noted that the means for controlling, operating and supporting the adjustable sections is entirely 25 concealed and contained in the wing between its fabric coverings and is thus protected and offers no resistance to the forward movement of the wing during flight.

It has been established that for making 30 a high rate of speed a comparatively flat wing or one having but a slight curvature from front to rear is most efficient. Where altitude flying is desired a wing having considerable curvature has been found best. 35 It is customary to have two or more sets of wings for an aeroplane and these sets have different curvatures. A set of wings is secured to the frame in accordance with the character of flying to be done. This 40 arrangement not only adds to the expense but is inconvenient and requires considerable time to make the change. Furthermore the curvature cannot be changed during flight.

It is apparent that by swinging the rock 45 shaft 18 of the wing herein described the sections 8 and 10 are adjusted. When said sections are swung downward the curvature of the wing from front to rear is increased but if said sections are swung upward the curvature is diminished. This adjustment 50 may be accomplished immediately and during flight and the aviator has at his command any desired curvature. As shown in Figs. 1 and 3 two of said wings are secured 55 to the frame 1. The rock shafts 18 are terminated adjacent each other and at one side of the frame. The said ends of the shaft are received in sockets 23 extending in opposed relation from a vertical sleeve 24 as 60 shown in Fig. 6. A lever 25 is loosely mounted in the sleeve but is confined against longitudinal movement by collars 26 and 27 fixed on said lever and bearing against the ends of the sleeve. On each rock shaft a 65 depending arm 28 is fastened adjacent the

socket 23 thereof. A cross lever 29 is centrally mounted and fixed on the collar 27 which is fixed on the lever 25. The cross lever 29 has its ends projecting through vertical slots 30 in the arms 28. By swinging 70 the lever 25 forward or rearward the arms 28 are swung and being fixed to the rock shafts the latter will be swung, the sockets 23 acting as bearings. By this movement the sections 8 and 10 of both wings or planes 75 are simultaneously swung either up or down depending upon the direction in which the lever 25 is moved. If the forward and rear sections 8 and 10 of one plane are swung upward and the forward and rearward sections of the other plane swung down any tendency of the aeroplane to lose its lateral equilibrium would be checked, as the sections swung down would oppose the sections which are swung upward. For effecting 80 this adjustment a lever arm 31 extends laterally from the lever 25 and is provided with a spring pressed latch 32 engaging a toothed collar 33 mounted on the sleeve 24. When the lever arm is swung it rotates the 85 lever 25 which rotates the cross lever 29. When the cross lever is rotated the arms 28 will be swung in opposite directions thus rocking the shafts 18 in opposite directions as will be apparent. 95

As hereinbefore stated the object of this invention is to diminish the "head resistance" and this is partially accomplished by the triangular frame and the provision whereby the curvature of each plane may be 100 reduced. By reducing the curvature of the planes it is evident that they will present less surface when moved forward and thus offering less resistance a higher rate of speed may be attained. The curvature of the 105 planes may be increased or decreased for several reasons and under different conditions. The adjustable plane herein described has a particular co-action with another invention involving the principles of 110 flight and for which I shall later file application for Letters Patent.

A bird in flying never permits its feet to hang or depend from its body but has them closely gathered into its plumage for the 115 reason that the feet and legs would offer resistance to the flight if they depended from the body. The running gear of an aeroplane bears the same relation to the frame as a bird's feet do to its body. As shown in the drawings I have provided a running gear which is hinged and arranged to be swung up against the frame thus obviating the resistance usually offered by the depending gear. From the under center portion of the frame 1 a tubular support 34 inclines downward and forward and terminates in a curved shoe 35 extending under the propeller 5. This support is held in position by a brace 36 also extending from 120

the frame. The shoe protects the propeller in case the machine strikes the ground with more force than will be offset by the shock absorbers of the running gear. To each side 5 of the frame wheel supports 37 are hinged. These supports are of the ordinary construction and are provided with the usual shock absorbers. From each support a spreader bar 38 extends forward to a block 10 or carriage 39 slidable on the support 34. Each bar 38 is pivoted at each end. Also from each wheel support another spreader bar 40 pivoted thereto extends rearward and upward and has pivotal connection with the 15 frame. An endless chain 41 passes over pulleys 42 mounted on the support 34, one run of the chain traveling through said tubular support. The chain is fastened to the block 39 and suitable means is provided 20 on the frame for imparting motion to one of the pulleys 42 and the chain 41. As shown in Fig. 2 the running gear is pendant and in position to support the machine on the ground, the block 39 being at the lower end 25 of the support 34. After the machine leaves the ground in ascending the aviator imparts motion to the chain 41 which slides the block 39 upward and rearward on the support 34. This swings the wheel supports 37 upward 30 and rearward against the frame as shown in dotted lines in Fig. 2. When it is desired to alight the chain is again manipulated to swing the running gear downward to its normal position.

35 It will be noted that the supports 37 are pivoted to the frame of the machine on a transverse axis well above the lower member 1 of the frame, so that the bearings of the arms or supports 37 are at widely separated 40 points at opposite sides of the frame. The sliding bearing connection of the arms 40 with the lower member 1 of the frame are made in the same manner as the connections of the arms 38 with the brace arm 34, a carrier 40' being movable along the member 1, and the arms 40 extending inwardly and rearwardly from the points of connection with the wheel supports to said carrier, so that as the supports 37 swing rearwardly 45 and upwardly they readily carry by the arms 40.

What I claim, is:

1. A running gear for aeroplanes, com-

prising in combination with a frame-work, an inclined slide-member carried by said frame, a carriage on said inclined slide-member, wheel supports pivoted to the sides of the frame, means operatively connecting said wheel-supports and said carriage, whereby, when said carriage is moved upwardly on said slide-member, said wheels are carried into said frame, and means for operating said slide.

2. A running gear for aeroplanes, comprising in combination, with a frame-work, 65 a fixed slide-member projecting downwardly from said frame-work, a carriage slidable on said slide-member, means for moving said slide on said slide-member, wheel-supports pivotally hung from said frame-work, 70 and pivotal connections between said wheel-supports and said slidable carriage, whereby said wheel-supports are swung into said frame-work when said carriage is moved upwardly.

75 3. A running gear for aeroplanes, comprising in combination with a frame-work, wheel carrying supports pivotally carried by said frame, a carriage mounted for movement upwardly into said frame, a rigid 80 slide-member for guiding the movement of said carriage, and means operatively connecting said wheel carrying supports and said carriage whereby said supports are carried upwardly into said frame, when said 85 carriage is actuated upwardly.

4. A running gear for aeroplanes, comprising in combination, with a frame-work, wheel carrying supports pivotally mounted on said frame, a rigid slide-member for 90 guiding the movement of said carriage, connecting rods pivotally joining said wheel supports and said carriage for throwing said supports upwardly into said frame when said carriage moves upwardly, the 95 operation being such that said wheel-supports are also drawn inwardly against said frame, and means for operating said carriage.

In testimony whereof I have signed my 100 name to this specification in the presence of two subscribing witnesses.

FRANK McCARROLL.
